UNITED STATES PATENT OFFICE

HECTOR RABEZZANA, OF FLINT, MICHIGAN, ASSIGNOR TO A C SPARK PLUG COMPANY, OF FLINT, MICHIGAN, A COMPANY OF MICHIGAN

SPARK PLUG AND METHOD OF MAKING THE SAME

Application filed December 7, 1928. Serial No. 324,512.

This invention relates to spark plugs for internal combustion engines, and more particularly to mica-insulated spark plugs in which annular constrictions and/or deformations of an outer metallic shell are employed to hold previously-compacted "washers" of mica or the like under radial compression such as to assure gas-tight joints.

This type is also of waterproof construction in that it is impossible for water to soak between the shell and insulator or stand in a pocket at the top of the plug as is the case in the conventional design of spark plug.

It is an object of this invention to provide spark plugs that require but few metallic parts, such as (1) a shell, collapsed after receiving an interior insulation, and (2) a shouldered washer, (3) an inner electrode, optionally tapered, and means such as (4) a collapsed nut to retain exterior insulation. Although affording large insulation surface, this construction is such that heat and pressure, as generated by the explosions in the engine, can have little or no detrimental effect even when these plugs are used in high compression, high speed, hot running engines toward which there seems to be a present trend.

It is another object of this invention, utilizing a discovery that radial compression may be satisfactorily transmitted through mica "washers" after they have been placed under high axial compression, to provide a spark plug in which such washers or the like are compressed by deformation of corresponding surfaces of shells serving as parts of plug bodies; and said bodies may initially comprise a zone or zones adapted to be thermo-plastically collapsed, as by a local heating under a pressure which compels said washers so closely to fit the other plug parts as substantially to prevent gas leakage.

It is a further object of this invention, in which a radial compression may be effected by the use of inwardly-diminishing electrode

heads or stems, to provide novel and improved methods of making spark plugs,—methods which facilitate accuracy, economy and speed in production, and low cost, and which provide exceptionally reliable and durable spark plugs, so designed as substantially to exclude water.

These methods preferably involve both a wedge fit and a local and suitably timed use of electrical resistance heating of the parts under pressure; but other objects of this invention (all forms of which may involve some use of a washer-receiving receptacular shell which initially includes an up-standing flange and/or a mentioned collapsible zone,— an inwardly-diminishing electrode head being optionally wedged therein after a taper-reaming operation, when such is included) will become apparent upon reference to the appended claims and the accompanying drawing, wherein

Figure 1 is an elevation, partly in section, of a spark plug made in accordance with the present invention;

Figures 2, 3, 4 and 5 are sectional views, and Figure 6 an elevation, partly in section, illustrating various steps in the method of assembling the plug parts;

Figure 7 is a sectional view of a portion of a spark plug illustrating a modification;

Figure 8 shows a further modification.

Referring to the drawing, the reference character 1 indicates the outer metal shell, having a screw threaded portion 2 at its lower end, an upwardly extending flange or lip 3 at its upper end, and a weakened wall portion 4 at an intermediate point. Positioned within the bore of the shell are several layers or "washers" of insulating material, such as mica, arranged in two groups 5 and 6, respectively,—the group 6 having a bore of larger diameter than the group 5, for a purpose which will later become apparent. On top of the insulating bodies is shown an apertured disc or washer 7 having a central

annular flange 8 and over which the up-standing lip 3 is swaged or bent upon the application of pressure, as is illustrated in Figure 3. In this figure there are shown die members 9 and 10, which are moved together against opposite ends of the shell 1, bending or guiding the lip 3 against the disc 7, thereby exerting a clamping pressure upon the laminated bodies and moving the several layers closer together, and locking the parts against subsequent separation. As soon as the parts are locked by the die members 9 and 10, the weakened wall 4 is preferably subjected to heat; further application of pressure by the die members 9 and 10 causes this wall to deform or bulge, thereby shortening the length of the shell and serving to radially compress the laminated insulation. The subsequent contraction of the metal upon cooling serves to still further exert a clamping pressure upon the layers of mica and upon a central electrode, if present. Otherwise, the top surface of the in-turned lip 3 may be machined or dressed down flat; and a reaming tool, such as indicated by the numeral 11, may be inserted in the central bore from the bottom to make the lower end of the bore tapered or cone shaped. A central electrode 12 having a tapered head or conical lower end 13 for seating engagement with the tapered surface of the insulation may be extended through the central bore to a point considerably above the top of the shell. An insulating sleeve 14 may be placed over the stem of the electrode and fitted through the central opening in the washer 7 and the opening in the insulator body 6. Laminated bodies 15 and 16 are shown placed on the stem 12 above the top of the shell 1, as is also a retainer or "nut" 17, having an annular groove therein to provide a weakened wall 18. The parts may be then inserted in the dies 9, 10 or dies 19 and 20, the die member 20 having a relatively movable stem 21 extending therethrough, said stem being shown as carried by pressure limiting means and as having a socket tip 23 for engagement with the lower end of the electrode to press it until secured in fitting engagement with the conical surface provided by the tapered bore in the body 5. Clamping pressure exerted by the die members mentioned compresses the laminated groups 15 and 16, and then causes the collapse of retainer member 17. The weakened wall 18 is preferably heated so that upon its collapse the material that is moved into tight contact with the screw-threaded end of the electrode will weld or fuse with the material of the electrode, thereby forming a permanent connection and one that serves both to hold the parts in assembly and the upper insulating body, comprising the laminated groups 15 and 16, under compression. The close fit between the several parts and the compression of the laminated

disc serves to effectually seal the plug against leakage of gas from the combustion chamber, head 13 preferably extending opposite bead 13'.

The insertion of the electrode 24 in the lower end of the shell in spaced relation with the electrode 12 to provide a spark gap, and the dressing down of the upper portion of the shell along the dot-and-dash lines shown in Figure 6 to afford a finished appearance to the plug, complete the several steps in the manufacture of the plug involved in the present invention, in some forms thereof.

In Figure 7 the central electrode 25 is surrounded by a long insulator sleeve 26 extending through the main insulation 27. Electrode 12 or 25 may be provided in its lower end with a flat head 28 fitting against a shoulder formed in the insulating body 27. The deformation of the weakened wall 29 of the shell 30, as previously described, exerts an inward force upon the insulation or upon a protective sleeve 31, tending to crowd the adjacent laminae radially. This causes the sleeve 26 to tightly hug or grip the sides of the head 13 or electrode 25, thereby providing an effective seal against gas leakage. The structure of the plug is otherwise as before described. The sleeve 14 or 26, if used, may be formed of mica; the sleeve 31 may be of comparatively thin and ductile metal; and any or all of the mentioned deformations may advantageously be effected in an electric welding machine comprising the mentioned dies,—somewhat as suggested by the use of plus and minus signs in Figures 3, 6 and 7; but the axial effect obtained by any application of heat and pressure to the deformable zone 4 may be observable mainly on a cooling thereof.

It will be obvious that dies 10 and 20 may be identical and stationary; that dies 9 and 19, then movable, may not be identical; and that die 21 (preferable, in point of convenience, to such means as might alternatively be employed to advance or place the stem 12 or 25 under tension before one or more retaining elements are locked thereon) may be supported by resilient means somewhat as symbolized by a compression spring 32, adapted to yield under a predetermined pressure.

In order to avoid separation or distortion of, or other harm to, the mica "washers" or equivalent insulation, any thermo-plastic or other inward collapse of the weakened region 4 or 29 of the receptacular shell 1 or 30, to effect a radial compression, obviously should occur, if at all, subsequent to any thermo-plastic or other inward deformation of the locking flange 3; and the die 9 and the flanges 3 and 8, or equivalent parts, may, in fact, be so proportioned and used as not only to effect and maintain a desired longitudinal or axial compression (and even to

obviate any machining of the die-contacted surfaces) but to produce, in the sequence indicated, the desired radial compressive effect,—obviating leakage past any suitable 5 insulation assembly within a shell.

It will be seen that all the described forms of present invention contemplate some use of sheaves of non-vitreous and substantially non-fracturable insulation snugly fitting a 10 special shell which is receptacular in form,—this being provided with an inner insulation receiving cylindrical or other corresponding surface which downwardly terminates in a flat or approximately flat washer-receiving surface 15 face (to seat a sheaf 5 or 28' of "washers", spacing an inner terminal portion of an electrode head) and upwardly terminates in a restraining part such as deformable flange 3; that any protective sleeve 31 employed to 20 effect a favorable distribution of pressure upon insulation (and whether integral with or distinct from the "washer" 7) may well be slightly shorter than the sheaf 27 of insulating washers to be thereby protected; and 25 that those embodiments suggested in Figures 7 and 8 obviously presuppose the use of some electrode-positioning means (which may be such as are suggested in Figure 6) during the placing of some of the "washers" 30 of any inner electrode assembly (as typified by sheaves 5, 5' and/or sheaves 27, 28 and 28') under radial compression,—the reaming operation suggested in Figure 4 being ordinarily used, to provide a tapered electrode seat, only in case a wedge-fitting or other inwardly-diminishing electrode is to be inserted subsequently to a radial compression,— 35 to be retained under tension by means such as a welded-on or other "nut" 18.

40 As suggested above and in Figure 8, regardless of whether or not means such as insulation-protecting tubes 31, 31' are employed opposite regions of deformation and for a pressure distributing or cleavage-preventing or other effect, and regardless of whether any members comparable to the flange 8 are provided (as by tubes 8', shown as separate from washers 7' and as adapted to receive mica or other insulating sleeves 53 26') any regions or parts opposite the flanges or beads resulting from deformation, and thereby subjected to radial pressure, may be 45 protected by yieldable metallic or other tubes of suitable length; and it is suggested in Figure 8 that an alternative or additional and intermediate sealing and retaining effect may be obtained by so proportioning the flange 3' and the tube 8', and so shaping the die 9' and retaining element 7' that, in addition to 55 60 or instead of any inward collapse of a weakened region 4 or 29, a suitable deformation of such a flange shall incidentally produce a sealing and electrode-gripping joint by an inward compression of insulating sleeve 65 26',—whether or not a protecting tube 8' is

interposed in addition to or in preference to any flange on the shouldered retaining washer element 7', and whether or not any suitably timed electrical or other heating is concurrently employed; but the suggested protection and a brief use of a softening electrical heat are both considered advantageous,—the electrical heating being favored by the local resistance due to a reduction in cross sectional area in the deformable region or 70 75 regions.

In that simple and very practical embodiment shown Figures 1 and 5, only the tapered head 13 and a so-called "nut" 18 need be employed as stop elements to retain under compression an outer (and at least part of an inner) insulation assembly assumed to be formed of mica or of a like non-vitreous material; but the concurrent use of axial compression and radial pressure, as provided for 80 by the delayed constriction effected at 4 (preferably opposite the taper of the head 13) is found to assure permanent tightness even in the case of this very inexpensive form,—both the effects of opposite or radially compressive movements of surfaces in assembling as described and the effects of enormous gas pressure which result from exposures during use being favorable to a tight gripping of an electrode stem and/or 85 a tight seating of the conical or other inwardly-diminishing head 13; and it will be appreciated that, although the collapsed or deformed receptacular shell might serve alternately as a bushing within a threaded body 90 carrying a grounded electrode, the incidental compression of an auxiliary sheaf of head-spacing "washers" or the like, as at 5' and 28', is an important merit of the described 95 construction and method.

100 Although the foregoing description suggests but a limited number of embodiments and advantages of this invention, it should be understood not only that various features thereof might be independently employed, 105 but also that numerous additional modifications thereof might easily be devised,—all without involving the slightest departure from said invention, as the scope thereof is indicated above and in the following claims.

110 I claim:

1. A method of producing a spark plug which comprises: disposing non-vitreous insulation and a shouldered element both within a receptacular shell which is provided also with an inwardly collapsible zone; and so collapsing said shell, while heating said zone, as to place said insulation first under axial and then under radial compression.

120 125 130 2. A method of producing a spark plug which comprises: disposing non-vitreous insulation and a shouldered element both within a receptacular shell which is provided also with an inwardly collapsible zone; and so collapsing said shell, while heating said zone,

- as to place said insulation first under axial and then under radial compression, said insulation comprising mica washers and an electrode being so inserted as to effect a gas-tight joint with some of said washers.
3. A method of securing an inner electrode in gas-tight relationship to mica washers surrounded by a metallic shell which comprises applying opposite pressures to the electrode and a retaining element therefor, and thermoplastically collapsing the retaining element.
4. A method of securing an inner electrode in gas-tight relationship to mica washers surrounded by a metallic shell which comprises applying opposite pressures to the electrode and a retaining element therefor, and thermoplastically collapsing the retaining element, said washers being taper-reamed while under compression, and said electrode being provided with an inwardly-diminishing head.
5. A method of producing a spark plug which comprises: disposing mica washers within a shell element having a corresponding inner surface, inserting an electrode element having an inwardly-diminishing surface; and producing such relative movement of one of said surfaces, while holding said washers compacted, as to effect a radial compression of some of said washers and to produce substantially gas-tight joints adjacent thereto.
6. A method of producing a tight joint between an outer shell element and an insulation assembly therein which is characterized by thermoplastically effecting an inward collapse of said shell while holding said assembly under axial compression.
7. In a method of making spark plugs that comprise axially-compacted non-vitreous insulation elements: compacting said insulation elements within a receptacular shell and thermoplastically so deforming said shell as permanently to retain said insulation elements under the desired compression.
8. A method of providing spark plugs with mica washers insulation held under radial compression between concentric conductive elements which includes manipulating one of said conductive elements to compress the insulation in a manner that such compression is radially transmitted, through said washers, to the other of said conductive elements.
9. A spark plug comprising: a receptacular metallic shell having non-vitreous flat washer insulation elements held under edge-wise compression therein by a collapsed part of said shell.
10. A spark plug comprising: a receptacular metallic shell having non-vitreous flat washer insulation elements held under radial compression therein by a collapsed part of said shell,—said part comprising an inwardly extending annular region, radially compressing some of said insulation elements.
11. A spark plug comprising: a receptacular metallic shell having non-vitreous insulation elements held under compression therein by a collapsed part of said shell,—said part comprising an inwardly extending annular region, radially compressing some of said insulation elements, and an insulation-protecting tube being disposed opposite said region.
12. A spark plug comprising: a receptacular metallic shell having non-vitreous insulation elements held under compression therein by deformed portions of said shell,—said portions involving an inwardly bent flange, for axial compression, and an inwardly extending bead, for radial compression of some of said insulation elements.
13. A spark plug comprising: non-vitreous insulation elements compressed within a shell and collectively providing a tapered electrode seat; and an inwardly-diminishing electrode retained under tension within said seat,—said shell being inwardly deformed and an insulating sleeve being disposed on said electrode opposite a region of inward deformation of said shell.
14. spark plug comprising: non-vitreous insulation elements compressed within a shell and collectively providing a tapered electrode seat; and an inwardly-diminishing electrode retained under tension within said seat,—said electrode externally carrying an insulation assembly which is retained under compression by a welded-on nut, said electrode comprising a wedge-fitting portion and said shell being provided with an inwardly-extending bead opposite the wedge-fitting portion of said electrode.
15. In a spark plug: an assembly of insulating washers; a conductive shell element snugly fitting the edges of the washers and retaining some of said washers under axial compression; an inner and tensionable conductive element extending through some of said washers; and a deformed portion associated with one of said conductive elements, for placing and retaining some of said washers under radial compression.
16. In a spark plug: an assembly of insulating washers; a conductive shell element snugly seating and retaining some of said washers under axial compression; an inner and tensionable conductive element extending through some of said washers; and means, comprised in one of said conductive elements, for placing and retaining some of said washers under radial compression, said shell comprising a region of inward deformation and a portion of said tensionable element opposite the region of inward deformation and a portion of said tensionable element opposite the region of inward de-

formation of said shell being surrounded by an insulating sleeve.

17. For use in a spark plug comprising an assembly of insulating washers: a receptacular shell element interiorly providing, near one end thereof, a seat for the direct reception and support of such washers,—said shell element being provided also with an inwardly deformable flange, at its opposite end, and
5 with an inwardly and subsequently deformable intermediate zone having relatively high electrical resistance.

In testimony whereof I affix my signature.
HECTOR RABEZZANA.
